UNITED STATES PATENT OFFICE.

EDWARD E. HEDLEY, OF NEW YORK, N. Y., ASSIGNOR OF ONE-HALF TO N. C. HEDLEY, OF SAME PLACE.

SMOKE-CONSUMER.

SPECIFICATION forming part of Letters Patent No. 317,775, dated May 12, 1885.

Application filed October 18, 1884. (No model.)

To all whom it may concern:

Be it known that I, EDWARD E. HEDLEY, of New York, county of New York, State of New York, have invented a new and useful 5 Improvement in Smoke-Consumers; and I declare the following to be a full, clear, and exact description of the same, such as will enable others skilled in the art to which it pertains to make and use it, reference being 10 had to the accompanying drawings, which form a part of this specification.

My invention consists of the combinations of devices and appliances hereinafter specified, and more particularly pointed out in the 15 claims.

In the drawings, Figure 1 is a section by a horizontal plane of a steam-boiler furnace embodying my invention. Fig. 2 is a vertical section of the same. Fig. 3 represents my de- 20 vice as applied to a locomotive-boiler. Fig. 4 is a separate sectional view in plan of one of the steam and air mixing and discharging chambers shown in Fig. 3. Fig. 5 is a vertical section of the same. Fig. 6 is a front 25 view of the boiler-furnace illustrating my invention. Fig. 7 is an enlarged sectional view of the steam and air connections illustrated by similar letters in Fig. 1.

My invention has for its object to effect a 30 thorough combustion within the furnace and consequent consumption of the smoke.

In carrying out my invention, A represents a boiler-furnace, B its front, and B' its side walls.

35 C represents the tube of my improved combining tube and chamber.

C' is the chamber, provided with a slot, c', through which the contents may issue into the furnace.

40 D is a steam-jet. This steam-jet is made with a shoulder, d, and an inverted conical nozzle, d', so that steam issuing from the contracted orifice in the jet expands more and more until it leaves the end of the jet. This 45 gives it a direction at once out toward the sides of the tube C. The size of the steam- passage in the jet as far as the shoulder d being the same as the steam-pipe with which it is connected, the body of steam is conveyed 50 intact to the shoulder, and thence injected into

the inverted steam-nozzle with more force un- 55 der a lower pressure than could be otherwise done with the jet formed without the shoul- der. The inverted nozzle allows the steam to expand before leaving the jet, so as to em- brace a large quantity of air with a small quan- 60 tity of steam. The interior of this tube, it will be observed, is wide opposite the end of the jet-tube, so that the issuing steam may gather a large quantity of air and drive the same for- 65 ward. At e the tube is contracted, so as to serve at this point the purposes of a combin- ing and accelerating tube. The chamber C' permits the contents to expand and become quite highly heated before they emerge from 70 the slot c'.

C' is a nipple, whereby the chamber C' is connected with the tube C.

D' is a supporting-bar, preferably of wrought-iron, cast in the tubes, and designed 70 to sustain the end of the steam-jet.

E is a cap, perforated at e for the free ad- mission of air. The purpose of this cap is to 75 secure the device of the boiler when it is de- signed for locomotives or similar boilers.

F, Fig. 2, is a steam-pipe leading from the steam-space of the boiler to a steam-box, F', located in the wall of the furnace, so as to be exposed to the strong heat of the furnace. A pipe, f, leads therefrom to the steam-jet D, 80 and if there be several of these steam-jets the steam-pipe may furnish steam to all said jets. The steam is thus reheated before it is used at the jet.

I would have it understood that the device 85 may be made either with or without this re- heating steam-box F'. I prefer, however, espe- cially in stationary boilers, to use the said re- heater, although in locomotive-boilers I pro- pose to dispense with the steam-box, convey- 90 ing the steam direct to the jet or jets.

G is a form of mixing and combining cham- ber which I prefer in stationary boiler-fur- naces, instead of the chamber C', (shown in 95 Figs. 4 and 5,) although it is substantially the same in principle, the tube being practi- cally elongated, and a somewhat different shape is given to the chamber. I provide this chamber G with slots g, located at differ- ent levels. I represent two such slots in the 100

drawings. The lower one is intended to spread the mixture of air and steam over the bed of fuel close to the latter, while the upper slot is designed to deliver the air and steam at a 5 level some distance above the fuel, in order to combine with and furnish the necessary oxygen to effect a consumption of such products as pass unconsumed through the lower stratum of air and steam.

10 The air may be taken directly from the exterior and be forced by the steam-jets forward into the furnace, and for ordinary purposes I generally employ the device in that way—as, for instance, upon locomotives; but where it 15 is desired to secure the greatest economy of fuel as well as the consumption of the smoke, I prefer to locate an air-retort, H, in the uptake or in the breeching at the end of the boiler, where the air may be thoroughly and highly 20 heated by the products of combustion which have passed through the boiler and are about to escape into the chimney or stack.

H' is a pipe leading to the tubes C.
H² is an air-inlet.

25 This air-box may be made of cast metal or of sheet metal or of boiler-plate, and this feature of providing an air-retort in the breeching or in the uptake for being heated by the waste products of combustion after they leave 30 the boiler and for the purpose of highly heating the air that is to be subsequently thrown into the boiler is an important feature.

In order to change the chamber C' (shown in Figs. 4 and 5) to the form of chamber shown at 35 the sides of the furnace in Figs. 1 and 2, it is only necessary to unscrew the chamber C and to screw into its place the long tube or neck shown in Figs. 1 and 2.

I represents a thimble, which passes through 40 the water-leg of the boiler shown in Figs. 3 and 4, so as to furnish a free opening for the smoke-consuming device.

It is apparent that the air-retort H may be employed upon a locomotive-boiler as well as 45 upon a stationary boiler, although in the former class of boilers it is frequently of little consequence to figure for such close economy in fuel, and the greatest consideration is to effect a thorough consumption, so as to prevent smoke.

50 The air-retort may therefore in such cases be dispensed with.

Having thus described my invention, what I desire to claim is—

1. In a smoke-consumer, a combining and accelerating tube, C, provided with an interior steam-jet formed with a shoulder, d, and an inverted conical mouth or nozzle with its contracted end next to said shoulder, whereby the

steam is conducted to the contracted end of the nozzle in the volume that it enters the jet, and 60 gradually expands until it leaves the nozzle, substantially as described.

2. In a smoke-consuming device, the combination of a steam-jet provided with a shoulder, d, and an inverted conical nozzle with its contracted end next to said shoulder, to bring the steam in volume to the contracted end of said nozzle, from whence it will gradually expand 65 till it leaves the nozzle, an embracing air-tube made wide for some distance in front of the 70 steam-jet, a combining and accelerating section, e, and a discharge slot or orifice, by which steam and air forced through the tube is discharged over the fuel, substantially as described.

75 3. In a smoke-consuming device, the combination of a steam-jet formed with a shoulder, d, and an inverted conical nozzle with its contracted end next to said shoulder, to bring the steam in volume to the contracted end of said 80 nozzle, from whence it will gradually expand till it leaves the nozzle, an embracing air-tube made wide for some distance in front of the 85 steam-jet, an air-retort located within the uptake of the furnace to be heated by the escaping products of combustion, and a pipe connecting said retort with the embracing air-tube around the steam-jet, substantially as described.

4. In a smoke-consumer, the combination of 90 a steam-jet formed with a shoulder, d, and an inverted conical nozzle with its contracted end next to said shoulder, to bring the steam in volume to the contracted end of said nozzle, from whence it will gradually expand till it 95 leaves the nozzle, an air-tube embracing said steam-jet, and a steam-superheating chamber connected with said steam-jet, and through which the steam passes before emerging from the jet, substantially as described.

100 5. In a smoke-consumer, the combination of a steam-jet formed with a shoulder, d, and inverted nozzle d', with its contracted end next to said shoulder, an air-tube, C, surrounding said jet and enlarged to a point beyond the 105 end of the jet and then contracted, an expansion-chamber, C', having an elongated slot, c', and a nipple, C², for connecting said expansion-chamber to the tube C, substantially as described.

110 In testimony whereof I sign this specification in the presence of two witnesses.

EDWARD E. HEDLEY.
